UNITED STATES PATENT OFFICE.

JAMES CHILDS, OF WALLSEND-UPON-TYNE, AND WILLIAM EVANS, OF WALKERVILLE-UPON-TYNE, ENGLAND, ASSIGNEES OF ONE-HALF TO SWAN HUNTER & WIGHAM RICHARDSON LIMITED, OF WALLSEND-UPON-TYNE, ENGLAND.

BULKHEAD AND THE LIKE.

1,420,305.

Specification of Letters Patent. Patented June 20, 1922.

Application filed January 12, 1921. Serial No. 436,632.

To all whom it may concern:

Be it known that we, JAMES CHILDS, of Brandlehow, Grange Villas, Wallsend-upon-Tyne, Northumberland, England, and 5 WILLIAM EVANS, of Walkerville-upon-Tyne, Northumberland, England, both subjects of the King of Great Britain and Ireland, have invented certain new and useful Improvements in and Relating to Bulkheads and the 10 like, of which the following is a specification.

This invention relates to partitions or bulkheads and the like structures and has for its object to provide an improved method 15 of construction and connecting structures of this kind together at right angles, or approximately so, whereby a metal to metal joint is obtained, the construction is considerably simplified, and the expense of the 20 same is reduced.

By the term "oil" in the following description any liquid that is carried in bulk by ships, or is stored on land, is to be understood.

25 Our invention has been mainly designed for oil-carrying steamers but it is evidently equally applicable to liquid-storing tanks on land. In the construction of the storage tanks of oil-carrying steamers as hitherto adopted, the interior of the tank is divided up into a number of compartments by means 30 of built-up partitions or bulkheads constituting angle-joints in which a number of partition plates meet approximately at right 35 angles to one another leaving a certain amount of vacant space between the ends of the said plates, that is, at the point where four adjacent compartments of the tank meet. It is very important that at the said 40 meeting point a thoroughly liquid-tight joint should be formed between the various adjacent compartments of the tank in order to prevent any leakage of oil from one compartment to another and heretofore it has

45 been necessary to plug or fill up the said vacant space by means of cement, a very laborious process which occupies a considerable amount of time and labour, especially owing to the large amount of riveting in 50 situ which was necessitated thereby.

Our present invention consists in an improved construction of partition or bulkheads of the kind referred to above whereby the structure is considerably lighter than

heretofore and can be largely built up in 55 the shops by means of power-riveting before being erected in situ on the steamer. The improved construction also enables a metal to metal liquid-tight joint to be obtained avoiding at the same time a large amount of 60 riveting and thus saving labour and expense. Also various other incidental advantages are obtained by the improved construction as will be pointed out hereinafter.

Examples of the improved construction 65 are illustrated in the accompanying drawings, in which Fig. 1 is a sectional plan view of a bulkhead cross-section on an oil-carrying steamer, shewing the junction of four compartments; Figs. 2, 3, and 4 illustrate modifications of the construction shewn in Fig. 1.

Referring to Fig. 1 of the drawings two aligned bulkhead plates 1 and 2 are shewn which are to be connected to form part of a bulkhead cross-section in the tank of an oil-carrying steamer, for example. According to our improved construction a plate 3 is riveted along its left hand edge to the inner edge of the plate 1 and along its right hand edge to the inner edge of the plate 2, these 70 connections being made by lap joints and secured by rivets 4, 4, and 5, 5, in the manner shewn.

In the form shewn in Fig. 1 we rivet or weld two T pieces 6 and 7 with their heads 85 directly opposite to one another and abutting against opposite sides of the plate 3. In the drawing these connections are shewn as being effected by rivets 8. To the web 9 of the T-piece 6 we now connect, preferably 90 by riveting, a bulkhead plate 10, and to the web 11 of the T-piece 7 we similarly connect a bulkhead plate 12. By this construction it will be seen that the bulkhead plates 1, 2, 95 and 10, 12, are connected together at right angles by a metal to metal joint by means of the cross-section comprising the members, 3, 4, 5, 6, 7, 8, 9, and 11.

The modification shown in Fig. 2 is adapted for the case in which two partitions 20, 100 21 are required to be somewhat near to one another. In this case a plate 3 is provided of sufficient width to extend beyond both of the said partitions 20 and 21, and at each cross-section a structure similar to that 105 shown in Fig. 1 is provided, except that the plate 3 is common to both cross-sections.

In the modification shewn in Fig. 3 angle

pieces 13 and 14 are employed instead of the T-pieces 6 and 7, shewn in Figs. 1 and 2, the principle of the improved construction being the same in both cases.

- 5 In the modification shewn in Fig. 4 the cross-section consists of a solid four-arm or cruciform piece 15, the bulkhead plates 1 and 2 being respectively connected to the arms 16 and 17 in one alignment, and the 10 bulkhead plates 10 and 12 respectively connected to the arms 18 and 19 in the other alignment. For this modification the piece 15 may be cast or rolled solid, or may be formed by welding pieces together.
- 15 Various other modifications may be made in the details of the improved construction or methods of connecting the parts without exceeding the scope of our invention, as will readily be understood.
- 20 By means of our improved construction of the partition or bulkhead the cross-section can be made as light as desired and the riveted seams of a centre line bulkhead can all be made in double shear. Many important 25 incidental advantages are also obtained, such as the following. The cross-section is greatly simplified thus involving an increased output of work. The construction of the cross-section being light can be adopted even where there are no special facilities for lifting and handling the cross-section after completion on the ground. Labour is reduced when assembling the cross-section which can be entirely power-riveted before 30 erection. The cross-section joint is absolutely metal to metal thus dispensing with

injection of vulcan cement and reducing the expense of drilling and caulking. All horizontal stiffening bars and connections for brackets can be riveted to the bulkhead 40 plates by hydraulic apparatus before erection. The total caulking required is reduced by 50 per cent.

This method of construction also considerably reduces the liability of leakage from 45 compartment to compartment and reduces the cost of testing these compartments.

What we claim and desire to secure by Letters Patent is:—

1. Construction of tank divided into a 50 number of compartments for the carriage or storage of a liquid in bulk, comprising in combination a cross-section formed of parts which are connected together metal to metal throughout to provide liquid-tight joints between adjacent compartments of the tank, and plates directly secured to the said cross section to form the partitions of the tanks.

2. In a tank having a number of compartments for the carriage or storage of a liquid in bulk, means for forming a liquid-tight joint between adjacent compartments, comprising in combination a solid four-arm section, which may be welded rolled or cast, and partition plating secured to each arm of 60 the said cross section to form a liquid-tight joint between four adjacent tank compartments.

In testimony whereof we have signed our names to this specification.

JAMES CHILDS.
WILLIAM EVANS.
